UNITED STATES PATENT OFFICE.

MAX VOGELGESANG, OF BROOKLYN, NEW YORK, ASSIGNOR OF ONE-HALF
TO HERMAN SCHWICKART, OF SAME PLACE.

POCKET-BOOK, HAND-BAG, OR THE LIKE.

SPECIFICATION forming part of Letters Patent No. 675,687, dated June 4, 1901.

Application filed February 18, 1901. Serial No. 47,765. (No model.)

To all whom it may concern:

Be it known that I, MAX VOGELGESANG, a citizen of the United States, and a resident of the city of New York, borough of Brooklyn, 5 in the county of Kings and State of New York, have invented certain new and useful Improvements in Pocket-Books, Hand-Bags, or the Like, of which the following is a full, clear, and exact description.

10 The object of the invention is to provide certain new and useful improvements in pocket-books, hand-bags, satchels, and the like, whereby a convenient independent change-pocket is provided entirely separate from the other 15 compartments of the article to enable the user to readily store change separate from bills, cards, handkerchiefs, and the like and to allow of conveniently removing such change without exposing and displaying the bills or 20 other contents of the article.

The invention consists of novel features and parts and combinations of the same, as will be fully described hereinafter and then pointed out in the claims.

25 A practical embodiment of my invention is represented in the accompanying drawings, forming a part of this specification, in which similar characters of reference indicate corresponding parts in all the views.

30 Figure 1 is a perspective view of the improvement arranged as a pocket-book. Fig. 2 is a transverse section of the same, and Fig. 3 is a side elevation of a hand-bag provided with the improvement.

35 The improvement illustrated in Figs. 1 and 2 consists, essentially, of a frame A, a main pocket A', and a separate change or coin pocket A², arranged at the top of the frame A, as is plainly indicated in said Figs. 1 and 2.

40 The frame A and the pockets A' A² have their main parts formed of two pieces of leather or other suitable material, the front part A³ of the main pocket A' terminating a suitable distance below the top A⁴ of the handle, on which the auxiliary change or coin pocket is attached, and the back A⁵ of the main pocket A' terminates in a flap A⁶, adapted to extend over the front piece A³ and overlap the same and be secured thereto by a suitable fastening device B.

45 The front piece A³, the front of the frame A, and the front piece

A⁷ of the change or coin pocket A' are formed of one single piece, while the back A⁵ of the frame A and the back piece A⁸ of the pocket A' are formed of the second or back piece, the 55 pieces being secured together along the rectangular frame portions by suitable stitches or the like.

The gussets for the main pocket A' are fastened to the front and rear pieces A³ and A⁵ 60 in any suitable manner, and said gussets D for the auxiliary pocket A² are similarly attached to the front and back pieces A⁷ and A⁸, and a suitable frame E is provided for this auxiliary pocket to permit of conveniently 65 opening or closing the pocket, as will be readily understood by reference to Figs. 1 and 2.

Now by the construction described and shown it will readily be seen that the main pocket A' terminates a short distance below 70 the top A⁴ of the frame A, so as to form an opening for the user's hand, while the auxiliary change or coin pocket A² extends upwardly from said top A⁴ and can be conveniently and readily opened or closed to place 75 the change or coin in said pocket or remove the same from the pocket whenever desired.

A ticket, card, or other pocket F may be attached to the back piece A⁵ of the main pocket A' for storing tickets, cards, handkerchiefs, or the like.

By having the main pocket A' entirely separate from the auxiliary pocket A² it is evident that the user can have ready access to any one of the pockets without disturbing or 85 exposing the contents of the other pockets, and at the same time a suitable handle is provided for conveniently carrying the article about.

As shown in Fig. 3, a hand-bag of any approved construction has its frame G' provided with a handle G², on the top of which is secured in any suitable manner a pocket H for storing coin or other articles, said pocket H extending to the top A², previously referred 95 to and shown in Figs. 1 and 2.

I do not limit myself to the particular construction of the pocket-book shown in Fig. 1, although by making the essential parts thereof of two single pieces considerable material 100 is saved and a very durable pocket-book is provided. I also do not limit myself to the

particular application of the device as shown, as it is evident the arrangement may be applied to other articles besides those enumerated.

5 Having thus fully described my invention, I claim as new and desire to secure by Letters Patent—

1. As a new article of manufacture, a pocket-book consisting of two pocket-books connected together, the connection between the books extending from the top of one to the bottom of the other and provided with an opening forming a handhold, as set forth.

2. As a new article of manufacture, a pocket-book consisting of two pocket-books connected together, the connection being provided with an opening, the rear wall of one pocket-box being extended and projecting through said opening to form a flap, as set forth.

3. As a new article of manufacture, a pocket-book consisting of a frame having the upper portion formed into a handle, a main pocket on the lower portion of the frame, and a change or coin pocket on the top of the handle, as set forth.

4. As a new article of manufacture, a pocket-book consisting of a frame having the upper portion formed into a handle, a main pocket on the lower portion of the frame, and a change or coin pocket on the top of the handle, the front of said frame, the main pocket and the change or coin pocket being of a single piece of material, and the back of said frame, the main pocket and the change or coin pocket being likewise of a single piece of material secured to said first-named piece of material, as set forth.

5. As a new article of manufacture, a pocket-book consisting of a frame having the upper portion formed into a handle, a main pocket on the lower portion of the frame, and a change or coin pocket on the top of the handle, the front of said frame, the main pocket and the change or coin pocket being of a single piece of material, and the back of said frame, the main pocket and the change or coin pocket being of a single piece of material secured to said first-named piece of material, as set forth.

coin pocket being likewise of a single piece of material secured to said first-named piece of material, and the covering-flap for the main pocket being an integral part of the back of the main pocket, as set forth.

6. As a new article of manufacture, a pocket-book consisting of a frame having the upper portion formed into a handle, a main pocket on the lower portion of the frame, and a change or coin pocket on the top of the handle, the front of said frame, the main pocket and the change or coin pocket being of a single piece of material, and the back of said frame, the main pocket and the change or coin pocket being likewise of a single piece of material secured to said first-named piece of material, the front of the main pocket terminating a distance below the top of the frame, to form a hand-opening in the frame, as set forth.

7. As a new article of manufacture, a pocket-book consisting of a frame having the upper portion formed into a handle, a main pocket on the lower portion of the frame, a change or coin pocket on the top of the handle, the front of said frame, the main pocket and the change or coin pocket being of a single piece of material, and the back of said frame, the main pocket and the change or coin pocket being likewise of a single piece of material secured to said first-named piece of material, the front of the main pocket terminating a distance below the top of the frame, to form a hand-opening in the frame, and a covering-flap for the main pocket and forming an integral part of the back for the main pocket, the covering-flap extending through said hand-opening, to overlap and be secured to the front of said main pocket, as set forth.

In testimony whereof I have signed my name to this specification in the presence of two subscribing witnesses.

MAX VOGELGESANG.
